US0D1072084S

(12) **United States Design Patent** (10) **Patent No.:** **US D1,072,084 S**
(45) **Date of Patent:** **** Apr. 22, 2025**

(54) **MODEL VEHICLE BODY**

(71) Applicant: **TRAXXAS, L.P.**, McKinney, TX (US)

(72) Inventors: **Adam Cole Ewing**, McKinney, TX (US); **Otto Karl Allmendinger**, Rowlett, TX (US); **Caleb Hix**, McKinney, TX (US); **Noah House**, Sachse, TX (US); **Trent Collins**, McKinney, TX (US); **Ross Martin**, Roanoke, TX (US)

(73) Assignee: **TRAXXAS, L.P.**, McKinney, TX (US)

(**) Term: **15 Years**

(21) Appl. No.: **29/894,952**

(22) Filed: **Jun. 15, 2023**

(51) LOC (15) Cl. **21-01**

(52) U.S. Cl.

USPC **D21/562**; D21/561

(58) **Field of Classification Search**

USPC D21/424, 427, 433, 434, 483, 533, 548, D21/549, 550, 551, 552, 553, 554, 559, D21/560, 561, 562, 564; D12/83, 87, 88, D12/92, 93, 96, 98, 99, 163, 164, 167, D12/169-172, 182

CPC A63H 19/15; A63H 17/004; A63H 17/00; A63H 17/05; A63H 17/002

(57) **CLAIM**

The ornamental design for a model vehicle body as shown and described.

DESCRIPTION

FIG. 1 is an upper, left, front perspective view of a model vehicle body showing our new design;
FIG. 2 is an upper, right, rear perspective view thereof;
FIG. 3 is a lower, left, rear perspective view thereof;
FIG. 4 is a lower, right, front perspective view thereof;
FIG. 5 is a front elevation view thereof;
FIG. 6 is a rear elevation view thereof;
FIG. 7 is a right side elevation view thereof;
FIG. 8 is a left side elevation view thereof;
FIG. 9 is an upper plan view thereof; and,
FIG. 10 is a lower plan view of the model vehicle body. In the drawings, the broken lines illustrate portions of the model vehicle body that form no part of the claimed design.

1 Claim, 8 Drawing Sheets
